UNITED STATES PATENT OFFICE

CLAUDIUS M. PETTY, OF WILKESBORO, NORTH CAROLINA

CONVENIENT UNION-ALLS

Application filed February 15, 1927, Serial No. 168,362. Renewed April 11, 1929.

This invention relates to garments of that type known as "cover-all" or "union-all", and has for one of its objects to provide a garment of this character which shall include a drop seat, a shirt extension underlying the drop seat, and tabs connected to the trousers and shirt extension for the purpose of preventing the shirt extension from working above the drop seat.

10 A further object of the invention is to provide a garment of the character stated wherein the drop seat may be readily lowered and raised and secured in the latter of said positions.

15 With the foregoing and other objects in view, the nature of which will become apparent as the description proceeds, the invention consists of the novel construction, combination and arrangement of parts hereinafter 20 fully described and claimed, and illustrated in the accompanying drawings, wherein:

25 Figure 2 is a side elevation of the upper portion of the trousers and the lower portion of the shirt of the union-all, illustrating the drop seat in partly lowered position,

30 Figure 3 is a view in rear elevation of the union-all,

Figure 4 is a view in side elevation of the upper portion of the trousers and the lower portion of the shirt illustrating the drop seat in partly lowered position, and 35 Figure 5 is a view in front elevation illustrating a slightly modified form of the belt of the union-all.

40 Corresponding and like parts are referred to in the following description, and designated in the several views of the accompanying drawings, by similar reference characters.

The union-all comprises a shirt 1 and trousers 2 of which the proximate edges of the front portions are sewed together as indicated at 3. The shirt 1 is provided with pockets 4 and a collar 5, and the open front side thereof is closed by buttons 6. The trousers 2 are provided with hip pockets 7, side pockets 8, and a pocket 9 for the reception of a rule, pencil or the like. The open front side of the trousers 2 is closed by buttons that are hidden by a placket 10.

The upper rear portion of the trousers 2 is free of permanent connection with the back of the shirt 1 and the upper front portion of the trousers, whereby to provide a drop seat 11 which may be readily lowered and raised and secured in the latter of said positions by a belt 12. The belt 12 is secured to the upper edge of the drop seat 11, and passes through loops 13 secured to the shirt 1 and trousers 2 at the front of the garment. Straps 14 having the appearance of belt loops, are secured to the drop seat 11 about the belt 12. The belt 12 buckles at the front of the garment as indicated at 15. In Figure 5 of the drawing there is shown a slightly modified form of the belt. This belt 12^a is not provided with a buckle, but instead one end thereof is provided with holes 12^b for the reception 70 of a button 12^c carried by the other end of the belt.

The shirt 1 is provided at its back with an extension 16 which underlies the drop seat 11. The shirt extension 16 is prevented from 75 working above the drop seat 11 by means of tabs 17 which extend rearwardly from the side edges of the upper front portion of the trousers 2 and which are stitched at their upper edges to the shirt extension as indicated 80 at 18 and 19, respectively. The drop seat 11 is provided at its side edges with inner flaps 20 which are secured at their lower ends to the tabs 17 and are provided with holes 21 for the reception of buttons 22 carried 85 by the tabs. The rear side edges 23 of the tabs 17 incline downwardly and outwardly to permit the shirt extension 16 to be raised after the drop seat 11 has been lowered. The shirt extension 16 is of considerable length 90 and extends to a point below the connection of the drop seat 11 with the trousers 2 and the point of connection between the tabs 17 and flaps 20.

As it is retained in place by the tabs 17, 95 the shirt extension 16 is prevented from working above the drop seat 11 by forward and downward bending movements of the body of the wearer, with the result that the garment will present a neat appearance, and the 100 back portions of the under garments of the wearer will be fully protected. By freeing the ends of the belt 12 or 12^a, the drop seat 11 may be moved into lowered position and thereafter the shirt extension 16 may be moved into its raised position. The garment is adapted for use by men and boys, it is comfortable to wear, and permits free use of the body and limbs of the wearer. It may be readily applied and removed, and may be made of any suitable cloth of any color.

What is claimed is:—

1. A garment of the character set forth, comprising trousers having a drop seat, a shirt having a rear extension underlying the drop seat, tabs secured to the trousers and shirt extension, inner flaps secured to the drop seat and tabs, means detachably connecting the tabs and flaps, and a belt connected to the drop seat.
2. A garment of the character set forth, comprising trousers having a drop seat, a shirt having a rear extension underlying the drop seat, tabs secured to and extending rearwardly from the side edges of the trousers and secured at their upper edges to the shirt extension, the rear side edges of the tabs inclined downwardly and outwardly, inner flaps secured to the side edges of the drop seat and having their lower ends secured to the corresponding ends of the tabs, means detachably connecting the flaps to the tabs, and a belt connected to the drop seat.

In testimony whereof I affix my signature.

CLAUDIUS M. PETTY.
